[57] CLAIM

The ornamental design for a spare tire holder, as shown
and described.

DESCRIPTION

FIG. 1 is a side elevational view of a spare tire holder
showing my new design, it being understood that the
tire is shown in broken lines for illustrative purposes
only and forms no part of the claimed design;

FIG. 2 is a side elevational view of the other side
thereof;

FIG. 3 is a front elevational view thereof with the
removable tire retainer plate broken away in the middle
for clarity of illustration;

FIG. 4 is a rear elevational view thereof;

FIG. 5 is a top plan view thereof;

FIG. 6 is a bottom plan view thereof;

FIG. 7 is a front elevational view of the removable tire
retainer plate thereof shown separately for convenience
of illustration, it being understood that the rear is a
mirror image of that shown; and

FIG. 8 is an elevational view of the edge of the remov-
able tire retainer plate of FIG. 7 it being understood that
each edge is identical to that shown.
